HYDRAULIC POWER TRANSMISSION APPARATUS

Piero Mariano Salerni, Westminster, London,
England, assignor to Marie Therese Elisabeth
Salerni, Nice, France

Application October 5, 1935, Serial No. 43,789
In Great Britain June 16, 1933

11 Claims. (Cl. 60—54)

This invention relates to hydraulic power transmission apparatus and has reference to hydraulic torque converting transmitters more especially for use in mechanically propelled vehicles.

5 The type of transmitter to which the present invention relates is that in which power is transmitted by circulation of liquid within a closed circuit due to difference in centrifugal head, as for example in the Föttinger or similar type of transmitter.

According to the present invention I provide an impeller having vanes shaped or curved to deflect the liquid backwards relatively to the impeller the angle or curve requisite to turn the liquid backwards relatively to the impeller beginning substantially at or extending substantially from the major radius of the circuit.

Further, according to this invention the delivery ends of the vanes are turned backwards relatively to the impeller or the direction of primary motion from a point in or near to the said major radius in such manner as to deflect the liquid backwards by a substantial angle relatively to the direction in which the liquid approaches the said point. By substantial angle I mean an angle of at least 20° but not so large as to cause the rate of revolution of the impeller to become so high, when transmitting power under the conditions for which the apparatus is designed, as to introduce losses which neutralize the increase of efficiency obtained by the said backwards deflection. The delivery ends of the impeller vanes are preferably arranged to extend beyond the point at which the circuit attains its major radius. The effect 35 of the arrangement according to the invention is to increase the efficiency of the transmitter. The turbine vanes may be substantially straight and radially disposed.

In order that the invention may be clearly understood and readily carried into effect, the same will now be more fully described with reference to the embodiment shown in the accompanying drawing, in which:

Figure 1 illustrates a sectional view of the circuit of one type of hydraulic power transmitter comprising an impeller, a turbine and a reaction or tertiary member and embodying the present invention.

Figure 2 is a diagrammatic developed view 50 showing an impeller vane and a turbine vane according to the invention.

In the example illustrated, the impeller is indicated by the reference letter A, having vanes A¹, the impeller being mounted on or connected with the driving shaft in any appropriate manner. The reference letter B indicates generally the turbine which is secured to the driven shaft in any appropriate manner, the vanes of the turbine being indicated by B¹. C indicates a tertiary or reaction member having vanes C¹ which,

when operative, function to deflect in the direction of primary motion the liquid issuing from the turbine. The said tertiary member may be of any appropriate type or form. With regard to the construction illustrated in Figure 1, the operation is generally as set forth in the specification of my patent application Ser. No. 730,161 filed June 11, 1934, so that further description with regard to the general operation and construction of the transmitter is not necessary. The present application is in part a continuation of my aforesaid application Serial No. 730,161. It is to be understood, however, that the present invention can be applied to other constructions. The present invention is concerned with the formation of the impeller vanes, and this formation is shown more particularly in Figure 2 which illustrates a preferred form of the invention diagrammatically. The impeller vane, which as aforesaid is indicated by the reference letter A¹ is, as shown, straight or radially disposed from its receiving end A² towards the major radius, whence it is curved or shaped so as to terminate in a deflecting portion A³ which is directed backwards relatively to the direction of primary motion by approximately 45°, which is a "backwards angle" that has been found to be adequate in certain cases, but it will be understood that the "backwards angle" can be varied according to requirements, so long as the angle is such as to deflect the liquid near the impeller outlet by a substantial angle relatively to the direction in which the liquid approaches the major radius of the circuit. In the example illustrated, the impeller portion of the circuit attains its major radius, at some distance from the delivery ends of the impeller vanes, for instance, as indicated at A⁴, the vanes being turned backwards from this point to their delivery and so that a substantial change in the direction in which the liquid flows through the impeller is effected near the impeller outlet. In this specification and in the claims the expression "major radius of the circuit" means that part of the circuit the outer boundary of which lies outside an imaginary cylinder of infinite length whose axis is the axis of rotation and which is just large enough in diameter to contain the inner boundary of the circuit.

In the example shown in Figure 1, X, X' is a section of the wall of the said imaginary cylinder, which intersects the outer boundary of the circuit at Y, Y'. The major radius of the circuit is the part of the circuit whose outer boundary is Y, y, Y', i. e. the part between the lines Y, Z, Y', Z' more remote from the axis of rotation, which lines are the shortest that can be drawn from the point Y, Y' on the outer boundary to the inner boundary. I have found that the arrangement according to this invention enhances the

efficiency of the apparatus. One of the advantages of the present invention is that it renders it practicable to avoid the use of turbine vanes of which the receiving ends are turned or curved 5 backwards relatively to the direction of primary motion as heretofore proposed for the purpose of decreasing impact losses. The turbine vanes are preferably arranged to be substantially straight and radially disposed as shown.

10. What I claim and desire to secure by Letters Patent of the United States is:

1. A hydraulic power transmitter wherein power is transmitted by circulation of liquid within a closed circuit due to difference in centrifugal head of the type wherein the torque imparted by hydraulic means to the turbine can be substantially greater than that imparted to the impeller and which comprises an impeller having its outlet in the major radius of the circuit 15 and delivering liquid having a component of velocity in the axial direction, a vaned turbine and a vaned reaction member, the vanes of the impeller forming ducts which near its outlet are turned backwardly relatively to the direction of 20 its angular motion from a point in or near to the said major radius by a substantial angle relatively to the direction in which the liquid approaches the said point, whereby the liquid is caused to leave the impeller with a component of 25 velocity in the direction of its angular motion smaller than that with which the liquid approaches the said point.

2. A hydraulic power transmitter wherein power is transmitted by circulation of liquid 30 within a closed circuit due to difference in centrifugal head of the type wherein the torque imparted by hydraulic means to the turbine can be substantially greater than that imparted to the impeller and which comprises a vaned impeller having its outlet in the major radius of the circuit 35 and delivering liquid having a component of velocity in the axial direction, a vaned turbine and a vaned reaction member, the impeller extending throughout a substantial portion of the 40 major radius of the circuit and having vanes forming ducts which near its outlet are turned backwardly relatively to the direction of its angular motion from a point in or near the major radius by a substantial angle relatively to the 45 direction in which the liquid approaches said point, whereby the liquid is caused to leave the impeller with a component of velocity in the direction of its angular motion smaller than that with which the liquid approaches the said point.

55. 3. A hydraulic power transmitter wherein power is transmitted by circulation of liquid within a closed circuit due to difference in centrifugal head of the type wherein the torque imparted by hydraulic means to the turbine can be substantially greater than that imparted to the impeller and which comprises a vaned impeller having its outlet in the major radius of the circuit 60 and delivering liquid having a component of velocity in the axial direction, a vaned turbine and a vaned reaction member, the impeller extending throughout a substantial portion of the major radius of the circuit and having vanes forming ducts which are turned backwardly relatively to the direction of its angular motion from a point at the beginning of the major radius of the circuit towards the outlet of the impeller by a substantial angle relatively to the direction in which the liquid approaches the said point, whereby the liquid is caused to leave the 70 impeller with a component of velocity in the

direction of its angular motion smaller than that with which the liquid approaches the said point.

4. A hydraulic power transmitter wherein power is transmitted by circulation of liquid within a closed circuit due to difference in centrifugal head of the type wherein the torque imparted by hydraulic means to the turbine can be substantially greater than that imparted to the impeller and which comprises a vaned impeller having its outlet in the major radius of the circuit 10 and delivering liquid having a component of velocity in the axial direction, a vaned turbine and a vaned reaction member, the impeller having vanes forming ducts which near its outlet are turned backwardly relatively to the direction of 15 its angular motion from a point in or near the major radius by a substantial angle relatively to the direction in which the liquid approaches the said point, whereby the liquid is caused to impinge upon and to be deflected by the backwardly curved parts of the vanes near their delivery ends and to leave the impeller with a component of velocity in the direction of its angular motion smaller than that with which the liquid approaches the said point. 25

5. A hydraulic power transmitter wherein power is transmitted by circulation of liquid within a closed circuit due to difference in centrifugal head of the type wherein the torque imparted by hydraulic means to the turbine can be substantially greater than that imparted to the impeller and which comprises a vaned impeller having its outlet in the major radius of the circuit and delivering liquid having a component of velocity in the axial direction, a vaned turbine 30 and a vaned reaction member, the impeller having its vanes disposed substantially radially from, or from near its inlet up to a point in or near to the major radius of the circuit and from the said point to or towards its outlet, having the 35 ducts formed between its vanes turned backwardly relatively to the direction of its angular motion by a substantial angle relatively to the direction in which the liquid approaches the said point, whereby the liquid is caused to leave the impeller with a component of velocity in the direction of 40 its angular motion smaller than that with which the liquid approaches the said point. 45

6. A hydraulic power transmitter as in claim 5, in which the vanes of the impeller are substantially radially disposed from the inlet end to a point at or near the major radius of the circuit and are then turned backwards. 50

7. A hydraulic power transmitter as in claim 1, comprising an impeller with vanes the backwardly turned portions whereof decrease in thickness gradually towards the delivery ends. 55

8. A hydraulic power transmitter as in claim 2, comprising an impeller with vanes the backwardly turned portions whereof decrease in thickness gradually towards the delivery ends. 60

9. A hydraulic power transmitter as in claim 3, comprising an impeller with vanes the backwardly turned portions whereof decrease in thickness gradually towards the delivery ends. 65

10. A hydraulic power transmitter as in claim 4, comprising an impeller with vanes the backwardly turned portions whereof decrease in thickness gradually towards the delivery ends. 70

11. A hydraulic power transmitter as in claim 5, comprising an impeller with vanes the backwardly turned portions whereof decrease in thickness gradually towards the delivery ends. 75
